US0D1064933S

(12) **United States Design Patent** (10) **Patent No.:** **US D1,064,933 S**
(45) **Date of Patent:** **** Mar. 4, 2025**

(54) **ELECTRIC BICYCLE**

(71) Applicant: **Xiaohe Electric Technology (Tianjin) Co., Ltd.**, Tianjin (CN)

(72) Inventor: **Yuchuan Li**, Tianjin (CN)

(73) Assignee: **Xiaohe Electric Technology (Tianjin) Co., Ltd.**, Tianjin (CN)

(**) Term: **15 Years**

(21) Appl. No.: **29/880,087**

(22) Filed: **Jul. 18, 2023**

(51) LOC (15) Cl. **12-11**

(52) U.S. Cl.

USPC **D12/111**

(57) **CLAIM**

The ornamental design for a electric bicycle as shown.

DESCRIPTION

FIG. 1 is a front view of a electric bicycle showing my new design;

FIG. 2 is a rear left view thereof;

FIG. 3 is a left view thereof;

FIG. 4 is a right view thereof;

FIG. 5 is a top view thereof;

FIG. 6 is a bottom view thereof; and,

FIG. 7 is a stereo view thereof.

The broken lines in the figures illustrate portions of the electric bicycle that form no part of the claimed design.
